COMBINED COFFEE TABLE AND LAMP

Robert Morris, Maricopa County, Ariz.

Application October 24, 1955, Serial No. 38,536

Term of patent 3½ years

(Cl. D33—14)

FIG. 1

I claim:

The ornamental design for a combined coffee table and lamp, as shown.
